(57) **CLAIM**

The ornamental design for quilted elongated steam pocket, as
shown and described.

DESCRIPTION

FIG. 1 is a top, rear and left side perspective view of the
quilted elongated steam pocket;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof; and,

FIG. 7 is a front elevational view thereof.

The broken lines shown are included for illustrative purposes
only form no part of the claimed design.
